ELECTRIC HEATING

Sidney J. Temple, Pittsburgh, Pa., assignor to
 Edwin L. Wiegand Company, Pittsburgh, Pa., a
 corporation of Pennsylvania

Application December 30, 1950, Serial No. 203,691

5 Claims. (Cl. 201—63)

1

My invention relates to electric heating, and the principal object of my invention is to provide an electric heating device having improved terminal means.

In the drawing accompanying this specification and forming a part of this application I have shown for purposes of illustration two embodiments of my invention, and in these drawings:

Figure 1 is a general view of the one embodiment;

Figures 2 through 8 are views illustrating one method of construction; and

Figure 9 is a general view of the second embodiment.

The embodiment shown in Figure 1 comprises a tubular heating element 10 including an open-end sheath 11, a resistor 12 extending longitudinally of the sheath 11 and provided with terminal pins 13 extending through the open ends of the sheath 11, and granular refractory material 14 provided to electrically insulate the resistor 12 and to conduct the heat from the resistor 12 to the sheath 11, but stopped short of the ends of the sheath 11, thus providing recesses 15 at the ends of the element.

As herein shown the element 10 is bent on itself, so that the two ends of the sheath 11 are adjacent and open in approximately the same direction, and suitably the refractory material 14 may be granular magnesium oxide formed by fusing and then crushing and screening to limit to an appropriate range of particle size.

Further the embodiment of Figure 1 comprises two conductor means 20, each including a conductor 21 butt-welded to the end of the respective terminal pin 13, as indicated at 22, and an electrical insulating covering 23 extending over the connection 22 and within the respective end recess 15 and held against displacement by the wall of the sheath 11 being crimped inwardly into the covering 23, as indicated at 24.

According to the present disclosure the conductor means 20 are assembled with the element 10 as indicated in Figures 2 through 8, in which Figure 2 indicates one end portion of the element 10 and Figure 3 indicates one end portion of one of the conductor means 20 in its initial condition.

Under the illustrated method, first the insulating covering 23 is retracted, as shown in Figure 4, exposing an end portion 25 of the conductor 21 of a length approximately equal to the extent of the terminal pin 13 beyond the face

of the refractory material 14, and also a next adjacent portion 26 of a length suitable to permit the subsequent welding operation.

Next the end portion 25 is removed, as indicated in Figure 5, and then the end of the adjacent portion 26 is butt-welded to the end of the terminal pin 13, as indicated in Figure 6, and thereupon the insulating covering 23 is caused or permitted to resume its original relation, and thereby comes into the position indicated in Figure 7, extending over the welded connection 22, within the end recess 15, and into engagement with the face of the refractory material 14.

15 According to the present embodiment, the wall of the sheath 11 is then crimped inwardly at 24, to retain the covering 23 in position, thereby providing the construction shown in Figures 1 and 8.

20 The embodiment illustrated in Figure 9 employs a two conductor cable 30 provided with single conductor extensions 31 corresponding to the conductor means 20 of the previous embodiment and applicable in the same manner.

25 From the foregoing it will be apparent that the described embodiments afford various advantages, including a completely covered connection, a relatively tight closure, low cost, and easy application.

30 On the other hand, obviously various changes may be made, and other embodiments constructed, retaining all or part of the present advantages, and therefore it is to be understood that the present disclosure is illustrative only, and 35 that my invention is not to be regarded as limited thereto, but to be of the scope defined by the appended claims.

Wherefore I claim:

1. The method of extending the terminal and 40 closing the terminal opening of a sheathed embedded resistor electric heater wherein a resistance conductor is disposed in a sheath and has a terminal end accessible through the opening in the sheath, and wherein the resistance conductor

45 is embedded in an electric insulating heat conducting refractory material which terminates short of the opening in the sheath to form with the sheath a pocket, which comprises retracting the insulating covering from the end of an electrical conductor having a mobile insulating covering thereon to expose the end of said conductor, connecting the exposed end of said conductor to said resistance conductor terminal, returning said retracted electrical conductor insulating

50 covering to a degree sufficient to cover the exposed

end of the electrical conductor and the accessible end of the resistor terminal, and into a position wherein the insulating covering is disposed in and substantially fills the pocket in the sheath, and then deforming that portion of the sheath forming the pocket to thereby produce a tight sealing engagement of the insulating covering with the internal walls of the sheath forming the pocket.

2. The method of extending the terminal and closing the terminal opening of a sheathed embedded resistor electric heater wherein a resistance conductor is disposed in a sheath and has a terminal end accessible through the opening in the sheath, and wherein the resistance conductor is embedded in an electric insulating heat conducting refractory material which terminates short of the opening in the sheath to form with the sheath a pocket, which comprises retracting the insulating covering from the end of an electrical conductor having a mobile insulating covering thereon to expose the end of said conductor, severing from the exposed end of said electrical conductor a length approximately equal to the length of the available end of the resistance conductor, connecting the exposed end of said conductor to said resistance conductor terminal, returning said retracted electrical conductor insulating covering to a degree sufficient to cover the exposed end of the electrical conductor and the accessible end of the resistor terminal, and into a position wherein the insulating covering is disposed in and substantially fills the pocket in the sheath, and then deforming that portion of the sheath forming the pocket to thereby produce a tight sealing engagement of the insulating covering with the internal walls of the sheath forming the pocket.

3. The method of extending the terminal and closing the terminal opening of a sheathed embedded resistor electric heater wherein a resistance conductor is disposed in a sheath and has a terminal end accessible through the opening in the sheath, and wherein the resistance conductor is embedded in an electric insulating heat conducting refractory material which terminates short of the opening in the sheath to form with the sheath a pocket, which comprises retracting the insulating covering from the end of an electrical conductor having a mobile deformable insulating covering thereon to expose the end of said

conductor, connecting the exposed end of said conductor to said resistance conductor terminal, returning said retracted electrical conductor insulating covering to a degree sufficient to cover the exposed end of the electrical conductor and the accessible end of the resistor terminal, and into a position wherein the insulating covering is disposed in and substantially fills the pocket in the sheath, and then deforming that portion of the sheath forming the pocket to thereby produce a tight sealing engagement of the insulating covering with the internal walls of the sheath forming the pocket and the external diameter of the available end of the resistance conductor.

15 4. The method of extending the terminal and closing the opening of a sheathed resistor-type electric heater having a terminal end of the resistor accessible from the sheath opening, which comprises retracting the insulating cover from an 20 end of an electrical conductor having a mobile insulating covering thereon so as to expose a length of the conductor, electrically connecting such exposed length to the terminal end of the resistor, returning the retracted insulating covering 25 and connecting it to the sheath of the heater to cover the electrical connection and to close the sheath opening.

5. The method of extending the terminal and closing the opening of a sheathed resistor-type 30 electric heater having a terminal end of the resistor accessible from the sheath opening, which comprises retracting the insulating cover from an end of an electrical conductor having a mobile insulating covering thereon so as to expose a length 35 of the conductor, electrically connecting such exposed length to the terminal end of the resistor, returning the retracted insulating covering and mechanically connecting it to the sheath of the heater to cover the electrical connection and to close the 40 sheath opening.
